HAIR CURLER

William Huppert, New York, N. Y., assignor to
Delamere Company, Inc., a corporation of Del-
aware

Application December 28, 1937, Serial No. 182,141

3 Claims. (Cl. 132—41)

This invention relates to a hair curler of the type comprising a winding form and swingable loop member, and more particularly to certain improvements in the loop member.

5 According to my invention, I provide a curler with a loop member having inturned ends each formed with an offset bend, and a split sleeve surrounding the proximate extremities of said in-turned ends to prevent any relative lateral move-
10 ments thereof.

My loop member may be easily applied to the curler and when so applied will be securely held against accidental disconnection with the two inturned ends supported in proper alignments
15 with respect to each other and in such a manner as to prevent the loop from wobbling while it is being swung about its pivot either into its closed or open positions.

An embodiment of the invention is illustrated in
20 the accompanying drawing in which:

Figure 1 is a top plan view of the curler showing the loop member in closed position;

Fig. 2 is a side view thereof;

Fig. 3 is an enlarged cross-sectional view taken
25 on the line 3—3 of Fig. 2;

Fig. 4 is a cross-sectional view taken on the line
4—4 of Fig. 3; and

Fig. 5 is a perspective view of the split sleeve,
30 showing the sleeve closed in dot-and-dash lines.

The hair form, shown in Figs. 1 and 2, comprises a cylinder member 10, preferably slightly tapered towards its outer end, and a finger member 11 which in its closed position overlies the cylinder member 10 for the major portion of its length. The two members are pivotally connected together, as by means of the annular eyes 12, or in any other suitable manner. A spring 13, in this instance in the form of a substantially U-shaped leaf spring, is provided to press the finger 11 normally closed against the cylinder 10 so that the ends of the hair may be engaged therebetween prior to winding the hair on the form.

45 14 is a wire loop member having inturned ends each comprising two substantially parallel portions 15 and 17 and a connecting portion 16. The two portions 15 and 17 are offset relatively to each other but lie in the same plane. When the hair has been wound on the form, the loop, as usual in such curlers, is swung down to its closed position, shown in Figs. 1 and 2, to clamp over the hair wound on the form so as to hold the hair from unwinding. The outer end of the loop may be provided with a roller or other means for

engaging the outer end of the cylinder 10 to lock the loop temporarily in its closed position.

A split sleeve 18, best seen in Fig. 5, is positioned around the proximate extremities 17—17 of the two inturned ends of the loop, the two ends of the sleeve being spread apart far enough to pass freely over said end portions of the loop. By means of a suitable tool, the ends of the split sleeve are then pressed together around the portions 17 of the ends of the loop member. This operation may 10 easily be effected by inserting the parts of the closing tool through the open ends of the curler before the spring 13 has been set in position.

In applying or assembling the loop to the form, first one of the inturned ends is inserted through 15 the opening in the eye 12 on one side of the curler, and then the other inturned end is similarly inserted through the opening in the eye on the opposite side of the curler. The offset bends of the inturned ends hold the loop securely in place 20 and serve to prevent accidental disconnection thereof from the form. The split sleeve 18, which surrounds the proximate inner extremities 17—17 of the two inturned end portions prevent 25 any appreciable relative lateral movement thereof and thus prevents the loop from wobbling when it is swung from open into closed position, and vice versa.

One of the disadvantages of the ordinary curler is that when the loop is being closed down over 30 the hair, it sometimes tends to become distorted with the result that either one of the inturned ends tend to slide inwardly, thus throwing the loop out of proper alignment. According to my invention, this disadvantage is overcome by the 35 provision of the sleeve that holds the extremities of the inturned ends in alignment with each other so that in manipulation of the loop, that is, in swinging it into or out of closed position, the portions 15 of the inturned ends always function 40 as the pivot points about which the loop turns.

Various modifications in the construction herein described may be made without departing from the scope of the invention. For example, the eyes 45 12 may be eliminated and in such case the in-turned ends of the loop may themselves serve as a means for pivotally connecting the cylinder 10 and the finger member 11. Means other than the spring pressed finger 11 may be used to hold the ends of the hair on the form prior to winding. 50

What I claim is:

1. A hair curler comprising a tubular form around which hair may be wound, a wire loop member pivotally secured to the form for engagement over the hair wound thereon, said wire loop 55

5 having inturned ends extending inwardly from opposite sides of the tubular form into the bore thereof, each of said inturned ends having two substantially parallel offset portions and a connecting portion all lying in the same plane, and a sleeve surrounding the proximate extremities of the inturned ends to prevent relative lateral movements thereof.

10 2. A hair curler comprising a tubular form around which hair may be wound, a wire loop member pivotally secured to the form for engagement over the hair wound thereon, said wire loop having inturned ends extending inwardly from opposite sides of the tubular form into the bore thereof, said inturned ends each having connected

15 offset portions, and a sleeve surrounding the proximate extremities of the inturned ends to prevent relative lateral movements thereof.

3. A hair curler comprising a tubular form around which hair may be wound, means on the 5 form for clamping the hair ends on the form prior to winding, and a wire loop member swingably secured to the form for engagement over the hair wound thereon, said wire loop having inturned ends formed with offset portions and extending 10 inwardly from opposite sides of the tubular form into the bore thereof, and a sleeve surrounding the proximate extremities of the inturned ends to prevent relative lateral movements thereof.

WILLIAM HUPPERT. 15
